UNITED STATES PATENT OFFICE

WARREN M. FLORANCE, OF BETHLEHEM, PENNSYLVANIA, ASSIGNOR TO BETHLEHEM
STEEL COMPANY, A CORPORATION OF PENNSYLVANIA

RAIL ANCHOR

Application filed December 1, 1930. Serial No. 499,277.

My invention relates to rail anchors and particularly to a one-piece double-acting type anchor constructed to engage a rail base flange on opposite sides of a tie and to be fulcrumed at an intermediate point to prevent the longitudinal creeping of the rail in either direction by the traffic moving over the rail.

One of the objects of my invention is to provide a rail anchor which is easily applied to a rail, which efficiently grips the rail base flange to retain the anchor in operative position on the rail and which cooperates with a stationary member of the roadbed to prevent the rail from creeping.

Another object of my invention is to provide a rail anchor which is applied to a railroad rail by distortion and which will be held in operative position by the tendency of the anchor to resume a condition from which it was sprung when applied to the rail.

A further object of my invention is to provide a one piece rail anchor which is adaptable to rails having base flanges of different widths.

Another object of my invention is to provide a rail anchor which will check the longitudinal creeping of the rail in either direction of traffic.

The novel features of my invention will be more fully understood from the following description and claims taken with the drawings in which:

Fig. 1 is a plan view of one form of my improved anchor.

Fig. 2 is a view of a portion of a railroad rail, a cross tie supporting the rail, a spike securing the rail to the tie and the rail anchor in its initial and operative positions on the rail.

Fig. 3 is a view of the right hand end of the anchor as shown in Fig. 2.

Fig. 4 is a section taken on line 4—4 of Fig. 2.

Fig. 5 is a view of the left hand end of the anchor as shown in Fig. 2.

Figs. 6, 7, 8, 9 and 10 are similar to Figs. 1, 2, 3, 4, and 5, but illustrating a modified construction of the anchor.

Referring to the drawings: 14 designates

and 18 and 19 the respective forms of rail anchors.

In the embodiment of my invention shown in Figs. 1 to 5 inclusive, the anchor comprises end members 21 and 22 and an intermediate connecting member 23 which is adapted to bridge a tie.

The anchor is preferably made from a bar of resilient metal of uniform section and its ends 21 and 22 are formed with notches 24 and 25 to provide shoulders or rail engaging members 26 and 27. The said members are formed so as to engage the bottom of one of the rail base flanges.

The connecting member 23 is preferably formed with a pocket or depression 28 which is adapted to pass over the head of a spike but out of gripping engagement with the upper surface thereof, so that the depending portion 30 will engage the rail adjacent the spike and the anchor will fulcrum on the rail base and not on the spike head.

The portion 30 also functions to engage the sides of the spike head upon the tendency of the rail to move longitudinally, and to engage the inner edge of the spike head upon the tendency of the anchor to move laterally of the rail so as to prevent the dislodgment of the anchor when it is in its operative position.

The anchor is applied to a rail by hooking its end 21 over the flange of the rail so that the shoulder 26 engages the under surface of the rail base and bringing the pocket 28 over the head of the spike so that the portion 30 is in engagement with the upper surface of the rail base flange. The anchor is now in the position indicated by dotted lines in Fig. 2. Pressure is now applied to the other end of the member 23, such as by placing the foot thereon, and a downward blow is struck with a hammer at the point indicated by the arrow in Fig. 2. This will cause the shoulder 27 to be brought into engagement with the under side of the rail base, the rail base flange having entered the notch 24. The shoulders 26 and 27 will now be in gripping engagement with the under surface of the rail base flange and the portion 30 is in gripping engagement with the upper surface of the rail

base flange due to the tendency of the anchor to resume its original condition before being sprung onto the rail.

In Figs. 6 to 10 I have illustrated a modified embodiment of my invention. In this modification the general features and principle of action and application are the same as for the anchor shown in Figs. 1 to 5 inclusive, the principal difference being the manner in which the fulcrum is formed on the member 35, and also that modified means are provided to prevent longitudinal and lateral movement of the anchor.

In this case the member 35 is depressed at 37 to form the rail base engaging portion 38 and the bar is further depressed at 39 to provide a tongue 36 which is adapted to enter an aperture 46 in the tie plate 16. The ends 40 and 41 are formed with notches 42 and 43, respectively, to provide rail engaging members or shoulders 44 and 45, respectively, which are adapted to engage the bottom of the rail adjacent the edge of one of the rail base flanges.

The method of application of this modified form, as shown in Fig. 6, is substantially the same as for the form shown in Fig. 2, that is, the end 40 is hooked over the rail base flange with the shoulder 44 engaging the under surface of the flange, the tongue 36 is inserted in the aperture 46 and the rail engaging portion 38 is brought into engagement with the upper surface of the rail base flange. The anchor is now in the position indicated in dotted lines in Fig. 6. Further application of the anchor is identical with that for the form shown in Fig. 2.

From the foregoing description it will be obvious to those skilled in the art that I have devised an improved one-piece rail anchor which is simple in construction, easily applied to the rail base and efficiently grips same to check the creeping tendency of the rail in either direction of travel. My device is particularly adaptable to rails having base flanges of different widths as it grips only one side of the flange of a rail its gripping ability is not affected by changes in widths of base flanges.

Another feature of importance is the fact that the anchor does not depend upon any member of the roadbed for its gripping effect on the rail.

While I have shown my invention in a plurality of forms, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

Having thus described the invention, what I claim as new and desire to secure by Letters Patent is:

1. A rail anchor comprising spaced end members adapted to engage one edge of a rail base, a connecting member for said end members adapted to bridge a tie and means connected to said connecting member adapted to engage the upper surface of the rail base flange. 76

2. A rail anchor comprising end portions adapted to engage one edge of a rail base flange, and an intermediate portion connecting said end portions, said intermediate portion having a depending portion adapted to engage the upper surface of the rail base flange adjacent the head of a track spike when said anchor is in its operative position on 80 the rail. 75

3. A rail anchor comprising end members adapted to engage one side of a rail, a connecting member for said end members, and means associated with said connecting member adapted to engage the rail intermediate 85 said end members and provide a fulcrum for said end members.

4. A rail anchor comprising depending end portions adapted to grip one edge of a rail 90 base, a member connecting said end portions, a depression in said connecting member adapted to provide a clearance for a spike head and means on said connecting member adjacent said depression adapted to grip a 95 rail base flange.

5. A rail anchor comprising spaced depending end portions adapted to grip one side of a rail, a connecting member for said 100 end portions adapted to bridge a tie and means depending from said connecting member intermediate the end portions adapted to grip the rail when the anchor is in its operative position.

6. A rail anchor comprising depending end members adapted to engage one flange of a rail base and a resilient member connecting said depending members adapted to bear with spring pressure against the aforementioned flange of the rail base. 105

7. A rail anchor comprising depending members formed with shoulders adapted to engage the underside of a rail base at one side of a rail, a resilient member connecting the upper ends of said depending members, said resilient member having depending means adapted to engage the upper surface of the rail base flange to distort the resilient member when the anchor is applied to a rail and to effect a gripping action between said shoulders and the base of the rail and the depending means and the upper surface of the rail base flange. 110

8. A rail anchor comprising depending members formed with shoulders adapted to engage one flange of a rail base, a resilient member connecting said depending members and adapted to bear with spring pressure against the upper surface of the rail base, said depending members adapted to be posi- 115

tioned on opposite sides of a cross tie when in operative position on a rail.

9. A rail anchor comprising a resilient rail engaging member adapted to bridge a railway cross tie and downwardly turned end members adapted to engage the flange of a rail base, said resilient member having a depressed portion to provide clearance for the upper surface of a spike head.

10. A rail anchor comprising spaced members adapted to engage one flange of a rail base on opposite sides of a cross tie, a member adapted to engage the upper surface of said flange intermediate said spaced members and connecting means for the aforementioned members.

11. A rail anchor comprising spaced members adapted to engage one flange of a rail base on opposite sides of a cross tie and a connecting member having means adapted to engage the upper surface of the rail flange above the cross tie, said connecting member adapted to be deformed from its normal position during the application of the anchor to the rail.

12. A rail anchor comprising a plurality of rail engaging members adapted to engage one edge of the rail base and means connecting said members adapted to overlie the head of a track spike but out of gripping engagement with the upper surface thereof.

13. A rail anchor comprising a plurality of rail engaging members adapted to engage one edge of the rail base, means connecting the ends of said members adapted to overlie the head of a track spike and in spaced relation with the upper surface thereof and means depending from said connecting means adapted to engage the rail base flange adjacent the spike head.

14. A one piece rail anchor for rails adapted to straddle a cross tie and to grip one edge of the rail base flange and to coact with the upper surface of the rail base flange above the tie when operatively applied to the rail.

15. A one piece rail anchor for rails having a plurality of members adapted to grip one edge of the rail base, means connecting said members adapted to bridge the head of a spike, said means having a depending portion adapted to contact with the rail base flange adjacent the spike head whereby the anchor will be held in frictional engagement with the upper surface of the rail base adjacent the spike head and at a plurality of points on the under surface of the rail base flange when the anchor is in its operative position.

16. A rail anchor adapted to bridge a cross tie comprising members for gripping one flange of the rail base at points on opposite sides of the tie and a member for gripping said rail base at a point above the tie.

17. In combination with a railway cross tie, a rail in position thereon and spikes for

limiting the rail against lateral movement upon the tie, a rail anchor having rail engaging members adapted to frictionally engage one edge of the rail base at opposite sides of the tie and another member adapted to frictionally engage the rail base above the tie, and to engage the sides of the head of a spike to resist longitudinal movement of said rail relative to said tie.

18. In combination with a railway cross tie, a rail in position thereon, a one-piece anchor having rail engaging members adapted to frictionally engage one edge of the rail base at opposite sides of the tie, and a connecting member having a depending portion adapted to engage the rail base above the tie to provide a fulcrum when one of said rail engaging members is moved downwardly to flex said connecting member whereby a gripping action is effected between the anchor and the rail.

19. In combination with a railway roadbed, a rail, a one piece rail anchor comprising spaced rail engaging members adapted to frictionally engage one edge of the rail base, means connecting said members adapted to bridge a tie and means associated with said connecting means adapted to frictionally engage the rail above the tie and to engage a relatively stationary member of the roadbed, whereby longitudinal movement of the rail is resisted.

20. A rail anchor adapted to be driven on to a rail comprising depending notched end portions adapted to grip one edge of a rail flange and a connecting member for said end portions adapted to bridge a tie and engage the upper surface of the base of the aforementioned rail flange.

21. A rail anchor comprising a portion adapted to fulcrum on a rail intermediate the edges of a tie and depending end portions having shoulders adapted to engage the base of a rail at each side of the tie respectively.

22. A rail anchor comprising end portions adapted to grip one edge of a rail flange, a connecting member for said end portions adapted to grip the upper surface of the rail flange, and a depending member associated with said connecting member adapted to engage a tie plate to prevent longitudinal movement of the rail.

23. A rail anchor comprising end portions adapted to engage one edge of a rail flange, a connecting member for said end portions adapted to bridge a tie and engage the upper surface of the rail flange and a depending member connected to said connecting member adapted to enter an aperture in a member of the road bed to resist the longitudinal movement of the rail.

In testimony whereof I hereunto affix my signature.

WARREN M. FLORANCE.
